FOUNTAIN PEN

Darrell C. Crain, Washington, D. C.

Application March 8, 1945, Serial No. 581,602

8 Claims. (Cl. 120—42)

1

This invention relates to fountain pens.

Fountain pens used heretofore have failed to satisfy all of the requirements, particularly in the quantity of ink contained where it was necessary to do a large amount of writing, it being of course inconvenient to have to stop to fill the pen.

Another deficiency in prior constructions is that the shape has not been completely satisfactory, and the pen has failed to conform to the hand of the user for free and easy use with the greatest comfort.

It is an object of the invention to solve the problems above enumerated and provide a fountain pen which will more nearly fulfill all of the requirements, including that of increased ink or writing fluid capacity and improved configuration so that the pen will better conform to the hand between the thumb and forefinger, thus being easily held and manipulated in the process of writing.

Another object of the invention is to provide a pen of enlarged ink reservoir capacity which can be easily carried in the pocket without consciousness of its increased size.

Further objects and advantages will be apparent from the following specification taken in conjunction with the accompanying drawings, wherein:

Figure 1 is a front elevation illustrating one application of the invention, the pen being shown with the cap on;

Fig. 2, a similar view with the cap removed and the pen ready for writing;

Fig. 3, a side elevation substantially at right angles to that of Fig. 1; and

Fig. 4, a top plan view.

Referring to the drawings, the fountain pen of the present invention consists of an ink container or reservoir 10 which has one small and one large end, the smaller end being circular and the large end being oval-shape in cross-section. The oval-shape portion of the pen is of substantially the same thickness as the diameter of the opposite end, but is wider to accommodate a much larger volume of ink or writing fluid in liquid form.

At the small end of the ink container is provided a pen holder 11 and a writing pen 12 adapted to be housed or enclosed by a cap 13 when the fountain pen is not in use. The holder 11 is provided with threads 14 adapted to be engaged by corresponding threads on the interior of the open end of the cap 13.

The enlarged oval end of the barrel 10 is provided with a counter-sunk cap retaining ex-

2

ternally threaded boss 15 to which the cap or cover is adapted to be attached when the pen is being used for writing.

The barrel of the pen may be filled in a well known manner and the pen may be provided with a fastener for securing the pen in the vest pocket, such fastener comprising an annulus 17 and a clip portion 18.

This wider portion of the barrel gives a relatively flat surface area on each side of the same which preferably is flexible so that the pen may be filled by manipulation of these flexible portions pressing them toward each other to increase the pressure within the barrel and thereby expel air therefrom and upon release the springiness or flexibility of the barrel by its return to normal will decrease the pressure and draw air or ink into the barrel.

It is to be understood when a barrel is used which is "preferably flexible" the comparable flexibility between the conventional rubber sack or ink containing element operated by pump 16 and the casing is such as to permit the pen to be held by normal handling and carrying pressures without causing leakage of the ink. In addition, the comparable flexibility between a conventional type rubber sack and a pen barrel is obviously such as to permit the rubber to give under much less pressure than does the barrel.

The design of the fastener is of such character that it will have sufficient flexibility to satisfactorily hold the pen when it is inserted in the vest pocket, while the relatively wide clip portion of the fastener will engage a sufficiently large area as to firmly engage but not damage the clothing.

A fountain pen of the above indicated construction is especially desirable and useful where a large amount of writing is necessary and an average amount of writing fluid required, and also particularly on account of the contour or configuration of the external surface of the barrel of the pen. This barrel is designed to more nearly conform to or fit between the thumb and forefinger of the hand, and substantially fill the space between the same, thus improving the manner in which it is held and by being supported over a much greater surface area, giving stability and at the same time affording free use of the writing instrument and the fingers and thumb of the hand, as well as supporting them restfully in position on the pen. It will be readily appreciated further that a fountain pen of a larger ink capacity is provided with the absence of the usual clumsiness and unwieldiness of over-sized pens.

Also the pen may be made small enough to be carried in a purse or in the vest pocket and yet have greatly increased ink capacity.

Due to the configuration of the pen, a place for an engraved plate or the like is provided. In addition, the gradually outwardly flaring oval top portion of the pen conforms to and fits between the thumb and forefinger while holding the pen in writing position. Thus one upwardly and outwardly curved edge of the pen lies comfortably and rests solidly against the length of the thumb, and the flat surface of the enlarged oval end is pressed firmly and solidly into the flat base of the V or U formed by the thumb and forefinger in conformity with their shape and clamping action during a writing operation. Where the forefinger is extended rather than crooked during a writing operation it likewise follows the contour of the pen placed or held in its normal holding position firmly clamps the curved contour of the pen against the thumb without undue pressure while the flat surface of the oval fits into and against the relatively flat surface formed at the base of the thumb and forefinger.

As heretofore described the enlarged flat oval portions of the pen casing are preferably somewhat flexible, due to the thinness of the walls, and by reason of this flexibility may be compressed slightly for removing an obstruction or for starting the flow of writing fluid to the pen point. As it is obvious from the drawing and description heretofore set forth, the walls of the pen barrel are relatively thin and when broadened to a flat surface as in the oval end may be flexed. That is, as well known in the pen industry, rounded or substantially rounded thin casings are relatively solid but unless reinforced by such shape or when in sheet form the material can be flexed as will be the case herein where the one end of the pen has been broadened to a flat oval shape. The flat sides of the oval requires more pressure to flex than is applied by the conventional filling arrangement as indicated.

It will be obvious to those skilled in the art that various changes may be made in the invention without departing from the spirit and scope thereof and therefore the invention is not limited by that which is shown in the drawing and described in the specification but only as indicated in the appended claims.

What is claimed is:

1. A fountain pen including a barrel having one end circular and the other end of enlarged flat oval shape providing increased writing fluid capacity, said oval portion having its side wall structure flexible for varying the pressure on the inside of the barrel, a cap for said pen and a cap receiving recess in the enlarged oval end of the barrel, and means in said recess for receiving and holding the cap.

2. A fountain pen of the character defined in claim 1 having its barrel tapered to conform to the space between the thumb and forefinger.

3. A fountain pen as set forth in claim 1 in which the sides of its barrel are concavely curved from its small to its enlarged end.

10 4. A fountain pen having a barrel with an end portion circular in cross-section and the other end portion of enlarged oval shape in cross-section, said barrel being of uniform thickness and tapering in width from its circular to its enlarged oval shaped end portion, said enlarged oval shaped end portion having relatively flat areas on opposite sides thereof which areas are flexible and by means of which the pressure on the interior of the barrel can be increased and by the return of the barrel to normal position the pressure on the interior of the barrel can be decreased.

20 5. A fountain pen of the character defined in claim 4 in which the enlarged oval shaped end is provided with a cap receiving recess, and means in said recess for retaining the cap.

25 6. A fountain pen including a barrel having one end circular and the other end of enlarged flat oval shape providing increased writing fluid capacity, a cap for said pen and cap receiving structure at the enlarged oval end of the barrel, for receiving and holding the cap.

30 7. A fountain pen having a barrel with an end portion rounded in cross section and the other end portion of enlarged flat oval shape in cross-section, said barrel tapering in width from its rounded to its enlarged flat oval shaped end portion whereby gripping of the pen barrel is facilitated.

35 8. A fountain pen having a hollow barrel with a small end portion and an enlarged oval end portion, said barrel tapering in width from its small end portion to its enlarged end portion, said enlarged oval end portion having relatively flat areas on opposite sides thereof whereby one tapered side of the barrel of the pen rests against the length of the thumb and one flat surface of the enlarged oval end rests across base of the U formed by the thumb and forefinger.
